DESIGN FOR A CABINET RANGE OR SIMILAR ARTICLE

Alvin G. Sherman, Grosse Pointe, Mich.

Application November 27, 1936, Serial No. 66,165

Term of patent 7 years

To all whom it may concern:

Be it known that I, Alvin G. Sherman, a citizen of the United States of America and residing at Grosse Pointe, in the county of Wayne and State of Michigan, have invented a new, original, and ornamental Design for a Cabinet Range or Similar Article, of which the following is a specification, reference being made to the accompanying drawing, forming part thereof.

The figure represents a perspective view of a cabinet range showing my new design.

The appearance of the side of the range not seen in the drawing is similar to the side which is shown.

I claim:

The ornamental design for a cabinet range or similar article substantially as shown and described.

ALVIN G. SHERMAN.
